UNITED STATES PATENT OFFICE.

SAMUEL W. HOWELL, OF BROOKVILLE, INDIANA.

MEANS FOR CONNECTING FLUES TO BOILER-SHEETS.

No. 911,897.

Specification of Letters Patent.

Patented Feb. 2, 1909.

Application filed July 3, 1908. Serial No. 441,824.

To all whom it may concern:

Be it known that I, SAMUEL W. HOWELL, a citizen of the United States, residing at Brookville, in the county of Franklin and State of Indiana, have invented certain new and useful Improvements in Means for Connecting Flues to Boiler-Sheets, of which the following is a specification.

The present invention provides a novel connection for uniting the ends of flues to the sheets of steam boilers, thereby admitting of the flues being removed when required and insuring a tight joint under all conditions and providing for packing the joints so that any space or wear may be compensated for.

For a full understanding of the invention and the merits thereof and also to acquire a knowledge of the details of construction and the means for effecting the result, reference is to be had to the following description and accompanying drawings.

While the invention may be adapted to different forms and conditions by changes in the structure and minor details without departing from the spirit or essential features thereof, still the preferred embodiment is shown in the accompanying drawings, in which:

Figure 1 is a perspective view of a portion of a boiler sheet embodying the invention. Fig. 2 is a longitudinal section of a portion of the boiler sheet, a flue and the joint between said flue and sheet, the parts being on a larger scale. Fig. 3 is a longitudinal section similar to Fig. 2, the nut and packing being removed and showing the formation of the end of the flue preliminary to upsetting its reduced extremity and the shoulder formed at the base of the reduced end.

Corresponding and like parts are referred to in the following description and indicated in all the views of the drawings by the same reference characters.

The boiler sheet 1 is formed with a series of bosses 2 in line with the openings and intended to receive the ends of the flues 3. The bosses 2 are externally threaded. Each flue 3 has an end portion 4 reduced and of a length to project beyond the nut 5 and to be upset or ribbed, as indicated most clearly in Fig. 2. The flue 3 is of a size to fit snugly within the boss 2 and the reduced end 4 projects through an opening in the end of the nut 5. The projecting end of the reduced

part 4 and the shoulder provided at the base of the reduced part 4, are upset or ribbed to overlap, respectively, the end of the nut 5 and the boss 2, thereby insuring the formation of a close joint between these parts and preventing contraction of the flue when cool and from moving inward through the boss or boiler sheet.

In assembling the parts, the end of each flue 3 is passed through the boiler sheet and boss 2, and the shoulder 6 at the base of the reduced end 4 of the flue is upset or ribbed so as to overlap the outer end of the boss 2. A washer 7 of asbestos or other material is slipped upon the reduced end 4 of the flue and is confined between the end of the boss and shoulder 6 and the end of the nut 5. The nut 5 is next threaded upon the boss and turned up tight to compress the washer 7 and insure the formation of a tight joint. After the nut has been screwed home, the projecting end of the reduced part 4 is upset or ribbed, as indicated in Fig. 2, thereby preventing inward movement of the flue with reference to the boiler sheet. Outward movement of the flue is prevented by the shoulder 6 engaging with the end of the nut 5 extending thereover. The great amount of metal provided at the joint, prevents the same burning out quickly or being readily affected by the change of temperature. The outer rib of the shoulder 6 engaging with the boss 2 and the outer rib of the reduced end 4 engaging with the end of the nut 5, prevent inward movement of the flue with reference to the boiler sheet when contracting.

Having thus described the invention, what is claimed as new is:

1. In combination, a boiler sheet having an opening and an integral boss extended outward from the sheet in line with said opening and exteriorly threaded, a flue fitted in said boss, and a nut threaded upon the said boss and having interlocking connection with the projecting end of the flue.

2. In combination, a boiler sheet having an opening and a boss extended outward from the sheet in line with said opening and exteriorly threaded, a flue fitted in said boss, and having a reduced end extended beyond the boss and having a shoulder at the base of the reduced end, a nut threaded upon said boss and having its end engaging with the shoulder formed at the base of the reduced end of the flue and having said reduced end

projected through an opening in the end of the nut and ribbed or upset.

3. In combination, a boiler sheet having an opening and a boss extended outward from the sheet in line with said opening and exteriorly threaded, a flue fitted in said boss, and having a reduced end extended beyond the boss, and having a shoulder formed at the base of the reduced end, said shoulder being upset or ribbed to engage with the outer end of said boss, and a nut threaded upon the boss and having its end engaging with the shoulder formed at the base of the reduced end of the flue and having said reduced end projected through an opening in the end of the nut and ribbed or upset.
4. In combination, a boiler sheet having an opening, and an externally threaded boss

in line with said opening, a flue fitted in said boss and having a reduced end, a shoulder formed at the base of the reduced end, said shoulder being upset to engage with the end of the boss, a washer mounted upon the reduced end of the flue, and a nut threaded upon the said boss and having its end confining the washer between itself and the end of the boss and shoulder formed at the reduced end of the flue, said reduced end projecting beyond the nut and upset or ribbed to overlap the same.

In testimony whereof I affix my signature in presence of two witnesses.

SAMUEL W. HOWELL. [L. S.]
